UNITED STATES PATENT OFFICE

2,573,162

THERAPEUTIC TRACTION DEVICE

Philip B. Terry, Jr., Hingham, and Horace R.
Stodder, Holbrook, Mass.

Application March 16, 1949, Serial No. 81,646

2 Claims. (Cl. 128—52)

1

Our invention relates to a therapeutic extension and traction device, and more particularly to a traction device designed for use in connection with the alleviation and/or cure of spinal disorders and their reflex and distal manifestations, by mechanically causing a slight and temporary separation of the segments of the vertebral column which later permits a more effective spinal manipulation by the operator of the device.

The principal object of our invention is to provide simple and portable apparatus to raise and lower a patient to cause a slight separation of the segments of the vertebral column to relieve lowback pain or the like resulting from muscular spasm or a trauma.

Another object is to make said apparatus or device unitary as well as portable, thus being easily moved from one patient to another.

The foregoing and other objects which will appear as the nature of the invention is better understood, may be accomplished by a construction, combination and operative arrangement of parts such as is disclosed by the drawings and specification. The nature of the invention is such as to render it susceptible to various changes and modifications, and, therefore, we are not to be limited to said disclosure; but are entitled to all such changes therefrom as fall within the scope of our claims.

In the drawings:

Figure 1 is a top plan view of my improved tractor device. Figure 2 is an end elevational view and Figure 3 is a side elevational view thereof.

Figure 4 is an enlarged sectional elevational view of the upper part of the structure shown in said Figure 2, taken on the line 4—4, and looking in the direction of arrows.

Referring to the drawings, the main supporting frame of our device has two lower frame bars 10 of any desirable material, but ordinarily of tubular metal, and of any desired length so as to provide stability to the entire structure. At each end of the bars 10 is mounted a caster 11, rotatable through a complete circle on a vertical axis. Approximately midway of the length of the said lower bars 10 and secured at their lower ends to them are upwardly extending tubular legs 12, which are of any desired or convenient length. Said lower frame bars 10 are arranged parallel to and spaced apart from each other any suitable distance, as for example, about three feet, or of a distance slightly greater than the width of a table or bed 13.

The upper ends of the legs 12 are secured to a

2

top 14, constituting the top for the main supporting frame. This top 14 is ordinarily substantially rectangular in plan view, as shown in said Figure 1, and is open and bordered with upstanding sides. As shown in Figures 1 and 2 our apparatus complete is easily moved into and out of position with relation to the bed or table 13.

Secured to the said top 14 and extending angularly downwardly therefrom at opposite sides thereof and adjacent the legs 12 are stationary arm supports 15, these supporting arms being further secured in position by braces 16 attached thereto and to said top 14. Pivotedly mounted at the free ends of the arm supports 15 are supporting levers 17, and pivotedly mounted to the free ends of the levers 17 is a lift or elevator bar 18.

Mounted on the top 14 is a motor M directly connected to a gear box reduction unit 19, which gives any desired reduction between the motor shaft and the shaft 20 of the gear reduction unit 19, and in the present instance a 150 to 1 reduction. Secured to the reduction unit shaft 20 is a crank arm 21 to which is pivotally attached one end of a connecting rod 22. The free end of the said crank 21 is provided with slot 22a to receive a stud 22b which adjustably holds said connecting rod 22 therein. The other, or lower end, of the connecting rod 22 is pivotally attached to a shackle 23 that is in turn secured to the elevator bar 18. 24 designates a sling for the holding of a limb or other part of the person to be treated and may be made of rubber, fabric, or other suitable material. This sling 24 may be secured to the elevator bar 18 in any desired manner, as by means of pins 26.

In operation our device may be wheeled into position with respect to the bed or table 13, as shown in Figure 1, and with the elevator bar 18 in appropriate position above the patient lying on such bed or table. Assuming that it is desired to apply traction to mechanically cause a slight separation of the segment of the vertebral column to relieve the lowback pain, the sling 24 is placed so as to be under the thigh of the patient, who is reclining on the bed or table 13. By starting the motor 19 in operation, the crank arm 21 is rotated about the shaft 20 as a center, thus moving the connecting rods 22 up and down, the extent of movement being indicated by the arc of the swing of the supporting levers 17, shown in dotted lines in said Figure 4, about the pivot connection thereof about the free end of the arm supports 15. The length of the up and down movement of the elevator bar 18 may be

varied by moving and setting the said stud 22b in said slot 22a to any desired position.

What we claim is:

1. A therapeutic traction device comprising a main supporting frame embodying a top, a motor supported by said top, a shaft connected thereto, an elevator bar at the upper portion of said frame and lower than said top, mechanism operatively connected to said elevator bar embodying a crank arm operatively connected to said shaft, a connecting rod connected to said crank arm, supporting means for said mechanism attached to said top, a supporting arm movably connected to said supporting means and to said elevator bar, and means connecting said connecting rod to said supporting arm whereby upon rotation of said shaft said crank arm, connecting rod and said supporting arm are moved to thereby move said elevator bar upwardly and downwardly.

2. A therapeutic traction device comprising a main supporting frame embodying two lower frame bars having casters, two legs connected to said bars, a top connected to said legs, a motor supported by said top, a shaft connected thereto, an elevator bar at the upper portion of said frame and lower than said top, mechanism operatively

connected to said elevator bar, embodying a crank arm operatively connected to said shaft, a connecting rod connected to said crank arm, supporting means for said mechanism attached to said top, a supporting arm movably connected to said supporting means and to said elevator bar, and means connecting said connecting rod to said supporting arm whereby upon rotation of said shaft said crank arm, connecting rod and said supporting arm are moved to thereby move said elevator bar upwardly and downwardly.
